UNITED STATES PATENT OFFICE.

HOWARD D. COLMAN, OF ROCKFORD, ILLINOIS, ASSIGNOR, BY MESNE ASSIGNMENTS,
TO EDGAR S. NETHERCUT, OF EVANSTON, ILLINOIS.

WINDER.

Application filed December 4, 1919, Serial No. 342,407. Renewed May 7, 1923.

To all whom it may concern:

Be it known that I, HOWARD D. COLMAN, a citizen of the United States, residing at Rockford, in the county of Winnebago and State of Illinois, have invented certain new and useful Improvements in Winders, of which the following is a specification.

This invention relates to winders of the class shown in Patent No. 1,267,977, dated 10 May 28, 1918, and comprising a traveling mechanism having means whereby power is shut off from the mechanism when the latter meets with an obstruction.

One of the objects of this invention is to 15 arrange the power-transmitting means so that it shall be operable by any one of a plurality of devices for detecting the presence of obstructions.

Another object is to provide means for 20 detecting the presence of a misplaced bobbin or other article lying in the path of the device that operates the bobbin-holders.

In the accompanying drawings, Figure 1 is a fragmental front elevation of a winder 25 embodying the features of my invention. Fig. 2 is a fragmental transverse sectional view. Fig. 3 is a detail view of a latch lever. Fig. 4 is a fragmental perspective view. Figs. 5 and 6 are views of one of the 30 detecting devices, Fig. 6 being a section on line 6—6 of Fig. 5.

Reference may be had to the before-mentioned Patent No. 1,267,977 and to an application Serial No. 342214, filed December 35 3, 1919, by Burt A. Peterson for a disclosure of a winder to which this invention may be applied.

Referring now to Fig. 2 of the present drawings, *b* denotes a tubular core on which 40 yarn is wound to form a cheese *c*. The core is removably mounted upon a suitable support, as, for example, a hub 30^a such as the one shown in my application Serial No. 74,290 filed January 26, 1916 (now Patent 45 No. 1,329,504, dated February 3, 1920). The hub is provided with means for locking the core in proper position on the hub. The hub is carried by an arm 30 which is pivoted at 31. The winder consists of a series 50 of winding units, each of which includes an arm 30. To economize space, the winding units are arranged relatively close together.

A carriage 88 is arranged to travel along the winder. To one end of the carriage 88 55 is attached a framework 89 which supports

mechanisms that operate upon the winding units. The carriage is provided with rollers, only two of which (90, 91) are herein shown. The rollers 90 and 91 run upon rails 86 and 92, respectively. The carriage 60 88 is caused to travel by means of a pinion (not shown) meshing with a rack 94. Power to actuate the mechanisms which are mounted on the framework 89, and to rotate the aforesaid pinion is transmitted 65 through a pulley 205 rotatably mounted on a shaft 206. The pulley is arranged to be connected to the shaft by means of a friction clutch member 209 fixed upon a sleeve 210. Said sleeve is slidable along the shaft 70 206, but the shaft is connected to rotate with the sleeve by means of a spline 210^a (Fig. 2). An expansion spring 211 surrounding the shaft 206 is interposed between the shoulder 212 on said shaft and a flange 213 75 on the end of the sleeve 210, said spring normally holding the clutch member 209 in engagement with the pulley 205. The clutch member may be withdrawn from engagement with the pulley by means of a contractile spring 216 which is connected to an arm 214^a of a hand lever 214. Said hand lever is mounted to swing on the axis 704. Rigid with the hand lever 214 is an arm 214^b which lies in contact with a pin 702 80 carried by a fork 703. Said fork is pivoted on the axis 704, and carries two studs 705 that lie at the side of the flange 213 opposite to that engaged by the expansion spring 211. The hand lever is normally held against actuation by the spring 216 by means of a latch arm 657 fixed upon a rock shaft 658. The hand lever 214 has a projection 659 (Fig. 3) which normally lies against a locking shoulder 660 on the latch 90 arm. Below the shoulder 660 is a shoulder 661.

It will be seen that when the latch arm 657 is swung upwardly, the spring 216 is released to action and immediately throws 100 out the clutch against the pressure of the spring 211.

Mounted on the framework 89 is means for promptly throwing out any cheeses that may be in running position when reached by the traveling mechanism, and for positioning successive cheeses with relation to the end-finder (not shown). This means comprises a throw-out plow 249 and a plow 250 located in position to lift the throw-out 110

cheese arms 30 onto a horizontal surface or dwell 251. Rearwardly of the dwell 251 is an incline 252 which lifts the cheese arms onto the dwell 253.

Referring to Fig. 2: If a cheese *c* be disengaged from the latch of the hub on which it is mounted, said cheese may be so far out on its hub as to foul upon an adjacent thrown-out arm 30, or such an unlatched cheese may prevent the adjacent cheese arm, when thrown out, from descending to its intended position. In order to throw out the clutch member 209 in the event of such a condition arising, I provide a plate or feeler member 267 rigidly attached to two arms 268 which are fixed upon a rock shaft 269. One edge of the plate 267 is of such outline as to define, in conjunction with the surfaces 251, 252 and 253, a passageway of sufficient width to admit a single cheese arm 30. If the traveling mechanism reaches a cheese arm which has been unable to descend to proper position, the inclined forward edge 274 of the plate 267 rides up on said cheese arm whereby the plate is lifted. Rigid with the plate 267 is a cam flange 267^a arranged to engage on arm 658^a on the rock shaft 658. When the plate 267 is lifted by an improperly-positioned cheese arm, the shaft 658 is turned in the direction to lift the latch arm 657, whereby the lever 214 is released and the spring 216 permitted to throw out the clutch member 209.

The plate 267 is yieldingly held in normal position by gravity.

A cheese may happen to fall into the space behind the series of brackets 48 disclosed in Patent No. 1,267,977, or the operator may lay some article in said space. To throw out the clutch member 209 in the event that the mechanism meets some such obstruction, I provide a feeder or plate 527 of suitable shape to travel through said space without unnecessary clearance. The upper part 527^a of said plate is shaped so as to be interfered with by a broken anti-bounder spring or other broken part that may project into the path of the portion 527^a. The plate 527 is attached to a slide 750 which is mounted in a guiding structure 751. The forward portion of the slide 750 rests upon a roller 752, while the rear end of the slide is provided with rollers 753 which move in guideways in the structure 751. A stop pin 754 (Fig. 5) in one of said ways serves to limit forward movement of the slide. Fixed to the slide is a plate 755 having a shoulder 756 which engages an arm 757, said arm being attached to a rock shaft 758. A torsion spring 759 surrounding the shaft 758 normally holds the feeler or plate 527 in its forward position. Rigid with the shaft 758 is an arm 760 to which is pivoted the lower end of a link 761. In the upper end of the link is a slot 762, in

which lies a pin 763 on a projection 764 on the latch arm 657. It will be evident that if the plate 527 collides with an obstruction, the arm 757 will be turned against the torsion of the spring 759, thus causing the locking shoulder 660 on the latch arm 657 to be disengaged from the projection 659 on the clutch-operating lever 214.

Means is provided for detecting a misplaced bobbin or other article in the path of the device that operates the bobbin-holders. While I have herein indicated a bobbin-holder of the type disclosed in an application Serial No. 323,194, filed September 11, 1919, by Burt A. Peterson, it will be understood that the present invention is not limited to any particular type of bobbin-holder. In Fig. 2 is shown a portion of the casing *x* of a bobbin-holder, and the plunger *y* by means of which the bobbin-holder is actuated to doff the spent bobbin and place the reserve bobbin in running position. A cam bar 677 is attached to the framework 89 in position to extend longitudinally of the series of bobbin-holders and operate the plungers *y* in succession.

A feeler arm 765 is fixed to and extends downwardly from the rock shaft 758. 765^a is a stop to limit the movement of the feeler arm under the action of the spring 759. The lower end of the arm 765 is bifurcated to straddle the cam bar 677 and the series of plungers *y*. The arm 765 is located near the forward end of the cam bar 677 so as to be engaged by a bobbin projecting from or lying upon a bobbin-holder or by any other obstruction which would interfere with the travel or operation of the cam bar 677. Upon striking an obstruction, the arm 765, which is rigid with the arm 760, will cause the latch arm 657 to be disengaged from the clutch-operating lever 214.

It will be observed that all of the feelers 267, 527 and 765 are arranged to operate a single means for throwing out the clutch to stop the travel of the carriage 88 and suspend operation of the winder-tending mechanism carried by the framework 89.

The shoulder 661 on the latch arm 657 prevents the hand lever 214 from being returned to running position until the latch arm has been lowered, and this latter cannot be effected until the obstruction which caused stoppage has been removed.

The slot 762 permits the latch arm 657 to be manually raised at will without the necessity of overcoming the torsion of the spring 759, and also relieves the plate 267 of the resistance of said spring.

I claim as my invention:—

1. A winder having, in combination, a cheese-arm feeler, a cheese feeler, a bobbin feeler, and a stop mechanism operable by any of said feelers.

2. A winder having, in combination, a

- clutch-operating lever, a latch arm arranged to lock the lever, a horizontal rock shaft to the forward end of which the latch arm is fixed, an arm attached to the rear end of the 5 shaft, and a pivoted cheese-arm feeler having a cam portion adapted to engage the last mentioned arm.
3. A winder having, in combination, a clutch-operating lever, a projection on said lever, and a pivoted latch arm having a shoulder adapted to engage said projection to lock the lever in running position, and a shoulder to engage said projection to limit 10 return of the lever toward running position, the last mentioned shoulder moving into effective position as the first mentioned shoulder moves out of effective position.
4. A winder having, in combination, a bobbin holder, a traveling device to operate 15 the bobbin holder, a device to feel for obstructions in the path of the first mentioned device, and a stop mechanism controlled by the second mentioned device.
5. A winder having, in combination, a bobbin holder, a carriage, a cam bar on the carriage to operate the bobbin holder, a device located near the forward end of said 20 bar to feel for obstructions in the path of the bar, and a stop mechanism controlled by 25 said device.
6. A winder having, in combination, a bobbin holder having a plunger, a carriage, a cam bar on the carriage to operate the plunger, an arm pivoted on the carriage, 30 said arm straddling the forward portion of the bar, and a stop mechanism controlled by said arm.
7. A winder having, in combination, a carriage, a slide on the carriage, a feeler 35 carried by the slide, a rock shaft on the carriage arranged to be turned by said feeler, a feeler arm connected to said shaft, and a stop mechanism controlled by said shaft.
8. A winder having, in combination, a winding unit, a carriage arranged to travel 40 past the unit, said unit comprising an upwardly extending bracket, a feeler mounted on the carriage in position to travel behind the bracket, another feeler mounted on the carriage in position to travel in front of the 45 bracket, and stop mechanism arranged to be actuated by either of said feelers.
9. A winder having, in combination, a supply yarn-mass holder, a carriage arranged to travel past the holder, a device 50 on the carriage to operate the holder, a feeler on the carriage extending into position to feel for an obstruction lying upon said holder, and a stop mechanism controlled by 55 said feeler.
10. In a winder, a supply yarn-mass holder, a carriage arranged to travel past the holder, a device on the carriage to operate the holder, and a feeler on the carriage extending into position to feel for obstruc- 60 tions lying upon said holder.
11. A winder having, in combination, a supply yarn-mass holder, a device to operate the holder, means to cause one of said 65 elements to travel past the other, a feeler associated with the holder-operating device and extending into position to feel for an obstruction in the vicinity of said holder, and a stop mechanism controlled by said 70 feeler.

In testimony whereof, I have hereunto set my hand.

HOWARD D. COLMAN.
